UNITED STATES PATENT OFFICE.

PETER WILLIS CAWTHON, OF HOUSTON, TEXAS.

SINGLETREE ATTACHMENT.

SPECIFICATION forming part of Letters Patent No. 552,417, dated December 31, 1895.

Application filed May 7, 1895. Serial No. 548,405. (No model.)

To all whom it may concern:

Be it known that I, PETER WILLIS CAWTHON, a citizen of the United States, residing at Houston, in the county of Harris and State 5 of Texas, have invented certain new and useful Improvements in a Singletree Attachment; and I do hereby declare the following to be a full, clear, and exact description of the invention, such as will enable others skilled in the 10 art to which it appertains to make and use the same.

This invention consists in an improved device on the end of a singletree to hold the 15 end of a harness-tug, and having the features made substantially as set forth hereinafter, and as shown in the accompanying drawings, in which—

Figure 1 illustrates the device in use. Fig. 2 shows sectional view of the device. Fig. 3 20 shows detail of parts separated.

A singletree A, of any suitable pattern, is used. On the end of this is fitted a peculiar ferrule B, to which is pivoted or hinged at C a holder D. The end of ferrule B is bevelled with a curve on the end, as shown. The 25 holder D is made saddle-like, so as to clasp the ferrule B with projecting flanges F, through which it is hinged by a pivot C. One end of holder D projects back as a handle H, 30 held up from the singletree by a spring G, as in Fig. 1, so the hand may press it down to turn it on its hinge. The other end of holder

D projects stirrup-like at L, over the end of ferrule B, in such way that it will engage with the tug K, between the end of ferrule B, and 35 this stirrup, so that when the horse draws forward on the tug the friction will draw the stirrup tight onto the tug, so as to bite onto and hold it, assisted by the spring G. When the handle H is pressed in on the spring the 40 other end of the part D passes back and loosens the bite on the tug, to release the horse.

Modifications may be made.

I claim—

1. A singletree having a ferrule B, with 45 a part D, hinged onto it formed saddlewise with two flanges, a handle H, and stirrup like part L, so as to engage with bite onto and hold the tug, substantially as set forth.

2. A singletree having a ferrule and a stirrup-holder hinged thereto with one end arranged to engage and hold the tug and the other projecting as a handle with a spring 50 therein arranged to hold the stirrup part onto the tug to avoid its becoming loose when slackened, substantially as set forth.

In testimony whereof I affix my signature in presence of two witnesses.

PETER WILLIS CAWTHON.
